Design No. 3,597, dated August 3, 1869.

DESIGN FOR A FURNITURE-LEG.

The Schedule referred to in these Letters Patent and making part of the same.

To all whom it may concern:

Be it known that I, GEORGE L. CHAPMAN, of Maumee, in the county of Lucas, and State of Ohio, have invented a new Design for Furniture-Legs; and I do hereby declare the following to be a full, clear, and exact description of the same, reference being had to the accompanying drawing, in which—

Figure 1 is an elevation of a piano-leg, carved in accordance with my design.

Figures 2, 3, 4, are horizontal sections of the same.

Figure 5 is a vertical section through the centre of the same.

This leg is octagonal in section throughout, with fluted faces extending along the middle section, as at A A, figs. 1 and 3. Said flutings are indented at the angles of the leg, as shown.

What I claim as new, is—

The design for a furniture-leg, herein shown and described.

GEO. L. CHAPMAN.
